UNITED STATES PATENT OFFICE.

EDWARD A. RIX, OF SAN FRANCISCO, CALIFORNIA.

HORSE-POWER.

SPECIFICATION forming part of Letters Patent No. 271,123, dated January 23, 1883.

Application filed November 22, 1882. (No model.)

To all whom it may concern:

Be it known that I, EDWARD A. RIX, of the city and county of San Francisco, State of California, have invented an Improved Horse-Power; and I hereby declare the following to be a full, clear, and exact description thereof.

My invention relates to certain improvements in horse-power machinery, in which a horse walking in a circle imparts motion to a drum upon which a hoisting-cable is wound.

It consists of an improved means for connecting the levers or sweeps to which the horse or horses are attached with the drum, so as to drive it, and a means for disconnecting it from the sweeps, so that the drum will remain stationary, or may be revolved in either direction; also in certain details of construction, all of which will be more fully explained by reference to the accompanying drawings, in which—

Figure 1, Sheet 1, is a perspective view of my apparatus. Fig. 2, Sheet 2, is a vertical section taken through the axis of the drum. Fig. 3, Sheet 2, is a plan view of part of the drum, with the sweep-sockets and the engaging and disengaging devices. Fig. 4 is a transverse section of the shaft B and spindle E.

A is a drum, which is made with a deep rim, so that considerable rope may be wound upon it. This drum may have two sets of arms, a, and hubs, as shown, and it is mounted to turn upon a fixed vertical standard or shaft, B, which has a flaring base, C, by which it is supported upon the timbers D.

The shaft B is made hollow, and a square spindle, E, passes up through it. The lower end of this spindle is connected by a link, F, with a bell-crank lever, G, which is hinged to the base C, so that it may be operated by the rod H and a lever, (not shown,) which is situated at any desired point outside of the line of travel of the horse. The upper end of the spindle E is made round and passes loosely through a head, I, which is thus allowed, when free, to turn upon the spindle, being kept in place by a pin. The head I has arms J projecting upward and outward at opposite sides in pairs, with anti-frictional rollers, between which the ends of the long arms K of two bell-crank levers pass. The angles of these levers form the fulcrums, and are pivoted upon the sweep-sockets L, so that the short arms K' pro-

ject downward into the inside of the rim of the drum. These sweep-sockets project in opposite directions to or beyond the rim of the drum A from a central hub, which turns loosely upon the standard B, above the wheel-hub, and the sweep M is bolted or otherwise secured into one of them; or, if necessary, two may be used, as the double sockets or holders are made with each machine, and no changes are necessary for the purpose of increasing the power when needed.

Around the upper part of the rim of the drum lugs N are secured at intervals, and in such relative positions that when the arms K' of the levers are thrown outward by allowing the inner arms, K, to drop down they will simultaneously engage the two lugs nearest in the direction which they are moving. These lugs are so constructed that the lever-arms will engage two opposite ones from either side, so that the drum may be revolved in either direction, and as they engage the lugs exactly in pairs the strain will be evenly divided. These lugs are placed at short intervals around the interior of the drum, so that they will be engaged by the lever-arms K very soon after they are thrown out, and the horse will not have to walk, as in most cases, nearly or quite half around the circle before the lever M is connected with the drum, so as to drive it.

A suitable break may be connected with the drum, so as to hold it and its load at any point after the horse-power is disconnected from it, or by which the load may be lowered while the horse continues his travel. When the lever-arms K' are thrown outward, they will engage a pair of the lugs N and move the drum almost immediately on account of the number of lugs, of which there may be as many as desired.

Having thus described my invention, what I claim as new, and desire to secure by Letters Patent, is—

1. In a horse-power, the fixed vertical shaft B, the winding-drum A, with its hub or hubs fitting the shaft so as to turn upon it, sweep or sweeps M, and the sweep holders or sockets L, with a hub turning upon the standard, in combination with the bell-crank levers K K', having their fulcrums upon the sweeps or their sockets, and the lugs N, fixed upon the rim of the drum, so that the levers may be engaged

with or disengaged from them by mechanism substantially as herein described.

2. In a horse-power, the drum A, mounted loosely upon the hollow vertical shaft B, and having the lugs or projections N, the sweep or sweeps M, turning loosely upon the shaft, and having the bell-crank levers K K' fulcrumed upon them, in combination with the spindle E, passing through the shaft B and engaging the levers K, the lever G, connected with its lower end, and the rod H, substantially as herein described.

3. In a horse-power, the drum A, with its lugs or projections N, and the sweep or sweeps

M, supporting the levers K K', and turning independently of the drum, the spindle E, passing through the shaft B and engaging the levers K, the operating-lever G, and connecting-rod H, in combination with the guiding and supporting arms J, between which the ends of the levers K pass, substantially as herein described.

In witness whereof I hereunto set my hand.

EDWARD A. RIX.
